UNITED STATES PATENT OFFICE.

EDWIN WILLIAM ROGERS, OF CHICAGO, ILLINOIS.

VALVE.

1,171,980.

Specification of Letters Patent. Patented Feb. 15, 1916.

Application filed February 4, 1915. Serial No. 6,081.

To all whom it may concern:

Be it known that I, EDWIN WILLIAM ROGERS, a citizen of the United States, and resident of Chicago, in the county of Cook and State of Illinois, have invented certain new and useful Improvements in Valves, of which the following is a specification.

My invention relates to locking valves for automobiles and has particular reference to 10 a novel valve member adapted for location in the intake manifold between the carbureter and the cylinder.

My invention is intended for use in connection with locking means such as disclosed 15 in the co-pending application of Edwin Rogers and myself, Serial No. 6001, filed concurrently herewith. As set forth in that application, it is not unusual to provide a lock of some sort for the ignition or in the 20 gasoline line but such locks are ineffective because of the ease with which the lock may be overcome and because of the fact that the carbureter of the engine contains at all times a considerable quantity of gasoline by means 25 of which the engine may be driven some distance without the necessity for a further supply of gasoline.

My invention contemplates the use of a 30 valve which shall be located in the intake manifold and which shall be of such peculiar construction that it may not be tampered with or broken open by any of the means at the command of an ordinary thief who has not an abundance of time within 35 which to tamper with the valve.

The invention will be more readily understood by reference to the accompanying drawings, wherein,

Figure 1 is an elevation showing merely 40 the location of the locking device, such location preferably being between the carbureter and the cylinders, in the intake manifold; Fig. 2 is a section on the line 2—2 of Fig. 3; Fig. 3 is a section on the line 3—3 of Fig. 2, and, Fig. 4 is an enlarged fragmentary detail showing the shaft lock.

Referring more particularly to the drawings it will be seen that I prefer to mount the valve or shutter in the intake manifold 50 10, and above the carbureter 11. This locking device may consist in a casing 12, having apertured ears 13, and provided with a through opening 14, of a size corresponding to that of the opening in the intake manifold. Top and bottom cover plates 15, 16, respectively are applied to the casing 12,

and are each provided with apertured ears of a size corresponding to those on the casing. These top and bottom cover plates may be pinned or riveted to the casing as at 60 17. The three parts are bolted to suitable flanges 18, 19, on the manifold and carbureter respectively, the bolts 20, which are used being of a hardened steel such as cannot be damaged by an ordinary hack-saw. 65 The nuts and the lower end of the bolts are apertured as at 21, and after the parts are in place a screw is entered in the aperture 21, and its head sawed or filed off. Thus the device cannot be removed from its location without drilling out the screw. Slidably mounted within the lower cover plate 16, is a shutter or valve 22, this shutter being provided with rack teeth 23, 24, on its upper surface, as best shown in Fig. 2. The rack teeth 23, are short whereas the teeth 24, are considerably longer. This shutter or slide is engaged and actuated by a pinion 25, securely mounted on the end of a shaft 26, which shaft is connected to a flexible shaft mounted in a flexible casing 27, and connected to a locking element which may be mounted on the dash of the car. The pinion 25, normally engages the rack teeth 23, during the opening and closing movements of 85 the valve the pinion being in register with the teeth 24, only in the closed position of the valve. The end of the shaft 26, which projects into the casing 12, has a bearing in a bracket 28, projecting downwardly from 90 the top cover plate 15. Inasmuch as it might be possible for a thief to sever the shaft and casing 27, and rotate the shaft thereby opening the valve, I have provided on the shaft 26, and bearing against the 95 pinion 25, a coiled spring 29, this spring tending to elongate the shaft and force the pinion into the longer teeth 24. When the pinion is in engagement with such teeth it will be seen that the valve cannot be opened 100 inasmuch as the pinion will have no meshing engagement beyond the extent of the teeth 24. This situation will occur in the event the shaft 26 is severed. However, the casing covering the shaft might again be severed at a point nearer the carbureter, the shaft retracted and the valve opened. To provide against this I locate on the bracket 28, a catch 30, held in position by pins 31, and provided with a notch or segmental cut-out portion 32. This cut-out portion is of a 110 less radius than that of the shaft 26, such

shaft being provided with a notch 32, of a size which will permit the catch 30, to engage therewith. The catch is urged into engagement with the shaft by means of a coiled spring 33. If the shaft 27, is severed the spring 29, will force the pinion and shaft to the right, as viewed in Fig. 2, whereupon the catch 30, will drop into the notch 32, and prevent the return of the shaft without taking the casing apart.

I believe this provides an extremely efficient locking device by means of which all possible use of the engine is prevented except by those authorized to use the same.

15 I claim:

1. In a valve, the combination of a casing having a cover, a slide valve in said casing, said valve being provided with rack teeth of different lengths, a pinion engaging said 20 rack teeth, and means for forcing said pinion into an inoperative position with relation to said valve, substantially as described.

2. In a valve mechanism, the combination of a casing, a valve mounted in said casing, 25 a pinion and shaft for operating said valve, means for forcing said pinion into an inoperative position with relation to said valve upon severing said shaft, and means for locking said pinion in such inoperative position, substantially as described.

3. In a locking valve for automobiles, the combination of a casing located in the intake manifold of an engine, a valve in said casing, a shaft and pinion for actuating said 35 valve, and means for locking said pinion with relation to said valve upon severing of said shaft, substantially as described.

4. In a valve for automobiles, the combination of a casing having an opening corresponding to the opening in the intake 40 manifold of an engine, a valve movable across said opening, a shaft for actuating said valve, and means for locking said valve operating means upon severing of said shaft, substantially as described.

5. In a valve of the class described, the combination of a casing having a cover, a slide valve having a rack upon one face thereof, said valve being mounted in the 50 casing, a pinion engaging said rack, a shaft for actuating said pinion, a spring normally

tending to elongate said shaft whereby said pinion is forced into an inoperative position upon severing of said shaft, substantially as described.

55 6. In a locking device for automobiles, the combination of a casing, a valve mounted in said casing, means for positively moving said valve to open and closed positions, said operating means being normally restrained from assuming an inoperative position, means operable upon the disarrangement of said operating means for locking said valve in closed position, substantially as described.

60 7. In a locking device for automobiles, the combination of a valve casing having a valve therein and provided with a cover, means for positively moving said valve to open and closed positions, and means for locking said valve in its closed position 70 upon disarrangement of the actuating means therefor, said locking means being disengagable only upon the removal of said valve casing cover, substantially as described.

75 8. In a device of the class described, the combination of a casing having a cover, a valve mounted in said casing, a shaft for operating said valve, a spring normally tending to elongate said shaft and to lock 80 said valve upon severing said shaft, the arrangement being such that the locking means may not be disengaged without removal of the casing cover, substantially as described.

85 9. In a device of the class described, the combination of a casing, a valve mounted therein, a shaft associated with and adapted to positively move said valve into open and closed positions, and locking means associated with said shaft and valve, said locking means being operable only upon the severing of said shaft, said locking means being located entirely within said casing, substantially as described.

95 Signed at Chicago, Ill., this 2nd day of February, 1915.

EDWIN WILLIAM ROGERS.
